UNITED STATES PATENT OFFICE.

WALTER EVERETT MOLINS, OF LONDON, ENGLAND.

DEVICE FOR FEEDING CIGARETTES.

Application filed July 20, 1925, Serial No. 44,948, and in Great Britain July 23, 1924.

This invention relates to improvements in feeding cigarettes and articles of similar shape in apparatus of the type wherein the articles pass from a hopper into substantially vertical channels or vanes.

Heretofore in apparatus of the type referred to it has been customary to remove the cigarettes or the like from below the vanes by means of a plunger or by a continuous conveyor having pusher pieces thereon, the cigarettes being removed in groups of one, two or more rows according to the height of the plunger or conveyor pusher piece.

In practice these methods of removing the cigarettes have been found to be unsatisfactory in cases in which the cigarettes vary in bulk or diameter.

In such cases the cigarettes form a varying bulk when superposed and a plunger or conveyor designed to remove, for example, three superposed rows of cigarettes is liable to remove cigarettes from a fourth row if the cigarettes run small in diameter, or to miss the third row if the cigarettes run large in diameter or are misshapen.

Further, when several rows are removed together, the lower rows cannot be inspected, whereas with the present method of removal each row can be seen by the operator.

The invention has for its objects to provide an improved method of and means for removing the cigarettes or the like in apparatus of the type referred to which shall be free from the above disadvantages.

According to the invention a suitably mounted table is arranged below the bottom of the channels or vanes, the clearance between the table and the vanes being preferably equal to approximately half the diameter of the cigarette or like article which is to be removed. The cigarettes or the like are then moved from beneath the vanes a row at a time by means of cross bars or the like preferably carried on two continuously rotated endless chains, into a channel in which a continuous conveyor operates. The single rows are superposed in the channel and when the desired number of rows have been superposed the bundle is moved by the conveyor to the packeting or other machine.

Improved means are also provided for compacting each row of cigarettes as it passes along the table, and for compressing, leveling

and squaring the bunch operated on by the continuous conveyor. Further improved means are provided for delivering rows containing an odd number of cigarettes to enable bunches to be formed comprising top and bottom rows of seven cigarettes each with a row of six in the middle or any other desired odd row formation as hereinafter fully described.

To enable the invention to be fully understood it will now be described by reference to the accompanying drawings in which:

Fig. 1 is a sectional elevation of a portion of a cigarette feeding apparatus having the invention applied thereto; and

Fig. 2 is an end view thereof.

Fig. 3 is a plan of the apparatus.

Fig. 4 is a side elevation of a portion of the apparatus for compressing the cigarettes; and

Fig. 5 is a part sectional end view thereof.

As shewn, the apparatus comprises a cigarette hopper 1 having vibrating vanes 2 between which the cigarettes pass to a sloping table 3 arranged beneath the bottom of the vanes.

The gap between the bottom of the vanes and the table is preferably equal to approximately half the diameter of a cigarette and through this gap bars 4 carried upon continuously rotating endless chains 4^a pass in order to remove a row of cigarettes from the table. The chains are carried on sprocket wheels 6, 7.

The wheels 6 are mounted on a spindle 8 carried in bearing brackets 9 and are driven by a sprocket wheel 10 which is driven in turn from any suitable source of power. The sprocket wheels 7 are each mounted on a short spindle 7^a so that the space between the chains is left free for the bars 4 to turn. It will be noted that the bars 4 are mounted on chain blocks 5 which are inverted, thus enabling the bars to turn in a small semi-circle at each end of the table. A slot 3^a may be cut in the table to allow dust and loose tobacco to fall through and holes may be formed in the machine bed beneath the slot to allow the dust to fall into trays beneath the machine. Since the purpose of this apparatus is to remove cigarettes in single rows at a time from beneath the vanes, the spaces between the vanes are made wider

than in cases where a whole superposed bundle of rows is to be moved at once to cover certain variations in size of the cigarettes, the cigarettes being always under the control 5 of the vanes even when lying on the table, since the gap is only equal to half the diameter of a cigarette. The cigarettes are, therefore, spaced apart somewhat widely on the table and the bars 4 are caused to carry the 10 row between tapering or curved side guides 12 to bunch up the row before pushing it off the end of the table. The guides 12 are spaced above the table 3 to enable the bars 4 to pass below.

15 The end of the table 3 is bevelled at *a* and the action of the bars 4 is to push the cigarettes a row at a time through the guides 12 and to allow them to fall into a channel or bed B in which pusher pieces 19 of an 20 endless conveyor operate.

25 As a row of cigarettes leaves the table 3 the rear ends thereof naturally tilt upwards and to avoid the possibility of a pusher piece 19 passing below the tilted ends, a cover plate 18 preferably of transparent material is fitted over the guides 12.

30 Thus the cigarettes are prevented from falling until their rear ends reach the bevel *a* on the table and they are allowed to slope until their front ends touch the bed, so that they fall gently and at the same time there is no possibility of them missing the pusher 19.

35 The channel B is fitted with side guides 11 forming a compartment into which the cigarettes are delivered in superposed rows by the bars 4. When the desired number of superposed rows has been delivered between the guides 11 the bunch may be compressed 40 by the compressor shewn in Figs. 3, 4 and 5.

45 The compressor comprises a sliding block 14 guided in a bracket 15 and operated from a cam 40 on the main spindle 41 of the hopper through a link 42 engaging a two-armed lever 43 mounted on a spindle 44, one arm thereof carrying a roller 45 which engages the slide of the block 14. As here shewn, the face of the block 14 is formed with projections 14^a which pass through slots formed 50 in the adjacent guide 11 to make contact with and compress the cigarettes.

55 If desired the compressor may be a plain block forming one of the guides 11 in its "out" position.

Over the top of the guides 11 a moving presser plate or leveller 16 is arranged, carried on a lever 17 pivoted at 17^a to one arm of a bell crank lever 46, mounted on the spindle 44. A roller 47 is mounted on the lever 46 engaging a cam 48 on the compressor slide. A spring 50 is fitted between the lever 17 and one arm of the lever 46, which yields if the leveller is stopped by any obstruction.

60 As the compressor slide is moved, the cam 48 causes the plate 16 to be lowered into

contact with the bunch of cigarettes and subsequently raised. This leveller plate may be independently operated if desired.

In front of the cigarette bunch a swinging leveller plate 18, pivoted between the 70 in Fig. 2 may be provided.

The apparatus is so timed that after a bunch of cigarettes has been compressed a pusher piece 19 on the conveyor moves the bunch forward and at this moment the leveller plate 16 operates to level the top of the bunch and simultaneously the forward ends of the bunch meet the plate 18 so that the bunch is squared neatly. As the cigarettes pass on, the plate 18 rises above the bunch 80 as shewn in full lines, Fig. 1, and falls into normal position when the bunch has passed. The squared bunch is then carried between guides 21 to the packing portion of the machine. 85

The compressing mechanism is only required when it is desired to pack the bunches in tightly fitting paper packets. If, for example, the cigarettes are to be packed into boxes of the slide and shell type the compressing machine may be omitted and the top leveller plate operated independently. 90

It will be seen, on reference to Fig. 1, that three conveyor bars 4 are arranged somewhat close together on the chains, leaving a considerable empty space on the chains. This allows the compressing and other movements to take place. Thus, in the arrangement shewn, three rows of cigarettes are delivered rapidly to the channel B, the timing being 100 such that the pusher piece 19 has just sufficient time to clear the bunch before the first row of the next bunch is delivered to the channel. 95

If it is desired to pack the cigarettes in 105 bunches having an odd number of cigarettes in one or other of the rows, a device shewn in Fig. 2 may be provided.

As shewn, a bell crank lever 26 is mounted on a spindle 23 rocking in a bearing 24 on 110 the vane brackets. At the lower end of lever 26 a bent plate 27 is mounted and the other end of the lever is linked to a rod 30 having a roller 29 engaging a cam 28 on the main spindle 41 of the hopper. Rotation 115 of the cam 28 causes the end of the plate to be projected into an opening formed in the adjacent vane slot preventing the cigarettes in that slot from falling. A spring 31 returns the parts to their original positions. Thus when the plate is in the vane slot the conveyor bars move cigarettes from beneath the other vane slots causing a row having one less cigarette than usual to be delivered 120 to the channel B. 125

This arrangement may be duplicated, on each side of the vane slots for example, or modified in various ways to suit different requirements.

The guides 21 may be fitted with strips 22 130

to hold the middle row of cigarettes in position in the known manner, when it is desired to pack bunches having upper and lower rows of seven cigarettes and a middle row of six cigarettes, for example. Obviously the apparatus may be used for packing bunches of any desired number of superposed rows and with any desired number of cigarettes in each row.

10 It will be understood that various modifications of the apparatus above described may be made. For example, the moving bars and the continuous conveyor may be replaced by suitable reciprocating members 15 if desired, or the conveyors moved intermittently.

I claim:

1. A cigarette feeding device comprising in combination a hopper adapted to hold 20 cigarettes, vertically disposed vanes arranged beneath said hopper and adapted to receive automatically cigarettes therefrom and arrange them in superimposed horizontal rows, a conveyer adapted to travel beneath said vanes and remove the cigarettes one row at a time therefrom and deposit the same in superimposed rows in a channel, and a second conveyer adapted to remove periodically a batch composed 30 of a predetermined number of rows of cigarettes from said channel.

2. A cigarette feeding device comprising in combination a hopper adapted to hold cigarettes, vertically disposed vanes located beneath said hopper and adapted to receive automatically cigarettes therefrom and arrange them in superimposed horizontal rows, a conveyer adapted to travel beneath said vanes and remove cigarettes one row at a time therefrom and convey them through 35 curved guides adapted to bring the cigarettes into contact with one another, a channel adapted to receive a predetermined number of superimposed rows of cigarettes from 40 said conveyer, and a second conveyer adapt-

ed to remove periodically a batch composed of a predetermined number of rows of cigarettes from said channel.

3. A cigarette feeding device comprising in combination a hopper adapted to hold 50 cigarettes, vertically disposed vanes located beneath said hopper and adapted to receive automatically cigarettes therefrom and arrange them in superimposed horizontal rows, a conveyer adapted to travel beneath said 55 vanes and remove the cigarettes one row at a time between guides adapted to press the cigarettes into contact with one another, a channel adapted to receive a predetermined number of superimposed rows of cigarettes 60 from said conveyer, a compression mechanism operable through slots in one of the guide members which constitute said channel and adapted to compress a batch composed of a predetermined number of rows 65 of cigarettes, and a second conveyer adapted to remove said batch from said channel.

4. A cigarette feeding device comprising in combination a hopper adapted to hold cigarettes, vertically disposed vanes located 70 beneath said hopper and adapted to receive automatically cigarettes therefrom and arrange them in superimposed horizontal rows, a conveyer adapted to travel beneath said vanes and remove cigarettes one row at a 75 time through guides adapted to press the cigarettes of each row into contact with one another, a channel provided with a compression mechanism and adapted to receive a predetermined number of superimposed 80 rows of cigarettes from said conveyer and compress them into a batch, means operatively connected to said vanes adapted to be automatically inserted between two or more vanes to arrest the movement of one 85 or more cigarettes of one or more of the rows comprising the batch, and a second conveyer adapted to remove periodically the batch of cigarettes deposited in said channel.
